R. C. COUPLAND

COUNTING OR REGISTERING APPARATUS FOR MACHINE GUNS

Filed Aug. 21, 1925

UNITED STATES PATENT OFFICE.

RICHARD C. COUPLAND, OF DAYTON, OHIO.

COUNTING OR REGISTERING APPARATUS FOR MACHINE GUNS.

Application filed August 21, 1925. Serial No. 51,586.

In operating machine guns especially of the aircraft type where the rate of fire is inordinately rapid, it is desirable that the gunner may constantly know the number of 5 rounds fired or the number of rounds remaining in the magazine. By reason of the restricted space imposed by the characteristics of the plane and the mounting of the guns only a limited supply of ammunition 10 may be carried which must be placed into belts, strips or magazines containing a relatively small number of rounds. Since continuous feed of the total available ammunition supply is impractical it is of vital importance to the gunner to readily know the 15 number of rounds remaining in the loaded belt or magazine so that he may avoid the danger of commencing an engagement with a depleted belt and the loss of time in changing or renewing belts when in the midst of combat.

The object of the present invention is to provide machine guns with a reliable automatic counting or registering apparatus and 20 in accordance therewith the feed mechanism is connected with a register or counter for indicating either or both the number of rounds fired and the number of rounds remaining in the loaded belt.

25 A further object of the invention is the provision of a counter or register having a frictional driven indicator, the frictional drive comprising a pair of split inter-fitting members, one extending within the other so that the inner member is provided with portions radially compressed by the outer member which extends around it. Such a frictional drive has been found to be far more satisfactory and dependable than the previously used disc clutches in registering devices.

To these and other ends, my invention consists in the construction, arrangement, and combination of elements, described 45 hereinafter and pointed out in the claims forming a part of this specification.

A practical embodiment of the invention is illustrated in the accompanying drawings, in which

50 Fig. 1 is a view in side elevation of a machine gun cover equipped with a registering apparatus constructed in accordance with the invention, the belt feed slide of the gun being omitted;

55 Fig. 2 is a transverse sectional view through the feed passage of the cover, the

registering apparatus being shown in elevation;

Fig. 3 is a sectional view on the line 3—3 of Fig. 4;

Fig. 4 is a sectional view on the line 4—4 of Fig. 3, and

Fig. 5 is a sectional view on the line 5—5 of Fig. 4.

Referring to the drawings by numerals 65 and characters of reference:

A registering apparatus or counter A is mounted over an opening B in the cover C of a machine gun above the feed passage D. A belt feed slide E of conventional type is reciprocated by the usual lever F which is actuated by the bolt in recoil and counter-recoil in a well known manner.

The register consists of a casing 6 having its under side partially closed by a plate 7 and is secured by screws 8 to the cover C. Disposed longitudinally in the lower central portion of the casing is a drive shaft 9 mounted on stubs 10 which are journaled in the front and rear wall of the casing where they are held by a spring 11 housed in the drive shaft. The drive shaft is provided with a spiral gear or worm 12 and a ratchet wheel 13 which is held against reverse movement by a catch 14 formed on a spindle 15 which is mounted parallel to and in the same manner as the drive shaft 9. A spring 16 wrapped about the spindle and having ends bearing against the casing and the catch forces the catch into engagement with the ratchet.

Loosely mounted on the drive shaft 9 adjacent the ratchet is a lever 17 depending through the cover with its free end inserted in an aperture 18 in the feed slide so that it will be oscillated as the slide is moved in operation of the gun. A stud 19 secured to the lever 17 intermediate its ends supports a pawl 20 and carries a spring 21 for holding the pawl into engagement with the ratchet wheel so that the drive shaft 9 is rotated upon the recoil stroke of the lever 17.

Mounted in the casing above and parallel to the drive shaft 9 is a driven shaft 22 having a split end which passes through and retains a pointer member 23, the members being connected by friction by having the split ends of the shaft 22 fit tightly within the pointer member 23. The fit between parts 22 and 23 is sufficient to prevent relative movement between the parts, due to the vibrations and shocks entailed in use on air-

planes and on a gun, but is of such value as to be easily overcome by the hand of the operator so that it may readily be reset. This form of friction drive connection is the most practical and effective one, and has been found to be extremely accurate and free from objections of the ordinary disk clutch. The driven shaft 22 is provided with a worm wheel gear 24 positioned directly above the gear 12 on the drive shaft.

10 A spindle 25 mounted vertically in the casing is provided with worm wheel 26 and worm 27, respectively in mesh with the worm 12 and worm wheel 24.

15 A dial 28 on the rear face of the casing may be conveniently divided and numbered from 0 to 100 in a counter-clockwise direction or any desired range of numbers corresponding to the number of rounds carried 20 by the magazine.

In operation of the gun, the lever 17 will be oscillated by the feed slide E and on the recoil stroke rotate the drive shaft 9 and associated gear train an amount sufficient to 25 move the pointer 23 a distance of one space on the dial. For example, when twenty rounds have been fired from the gun the hand of the pointer will coincide with the numeral 8 indicating to the gunner that 30 eighty rounds remain in the magazine. On renewing a belt the pointer may readily be

returned to zero by manipulating the knob 23'.

Should it be desired to keep a record of the total number of rounds fired to determine the life of a gun or any of its parts there may readily be associated with the pointer a suitable indicator for registering the consumption of ammunition in hundreds.

40 I claim:

1. In a register, in combination, a casing, a counting mechanism in said casing, a split shaft driven by said mechanism and an indicator shaft coaxial with said first shaft and frictionally engaging the same to allow the 45 resetting of the indicator, said shafts frictionally pressing each other in a radial direction.

2. In a register in combination a reciprocating element, a counting mechanism operated thereby, a rotatable shaft driven by said mechanism, an indicator pointer, a pointer shaft supporting said pointer, said shafts being mounted one within the other and both of said shafts being split so as to be in frictional engagement with the split portions of the inner shaft pressing outwardly in a radial manner on the split portions of the outer shaft.

50 55 In testimony whereof I affix my signature.

RICHARD C. COUPLAND.
